(57) **ABSTRACT**

A hand tool that has a pliers-like body and a special head. The head has a pair of parallel teeth that fit onto the grooves of a zipper guide. As the tool is squeezed, the teeth force the grooves closed uniformly and symmetrically. In this way, the tool can adjust the grooves on all types of zippers quickly and easily. Such a tool can be used on all types of zippers, such as those found on tents, clothing, tote bags, luggage and many other things.

BACKGROUND OF THE INVENTION

1. Field of the Invention

This invention relates to zipper repair tools and particularly to hand-held, pliers-like zipper repair tool.

2. Description of the Prior Art

Zippers have been used for well over 100 years. A typical zipper has a pair of strips that have teeth that are interlocked together in a guide as the guide passes over the teeth. The guide has a pair of grooves in which the teeth segments slide to facilitate interlocking. If the guide is damaged, the zipper will not work. Guides can be damaged, or if either side of the zipper guide is not symmetrical in relation to the other side, the zipper teeth will not properly mesh to ensure proper closure. For example, if the grooves are compressed to where the teeth can no longer enter the grooves, the zipper will not work. The more prevalent problem, however, is when the grooves are spread or distorted so that the teeth are no longer held in proper alignment within the grooves. Often, people may try to close the grooves using a tool like pliers to push the grooves closed. The problem with this approach is that it gives the user no control over the adjustment of the groove in relation to each other. It is easy to squeeze the groove too much on one side and thus completely distort the guide assembly. If the grooves are compressed too much, they must be opened again by prying them apart. Often this is done using a screwdriver or a similar tool. As before, there is no control on how much the grooves will be opened. Moreover, excessive force can cause the grooves to break. Finally, there is no simple way to ensure that the grooves are symmetrical and uniform using this technique. Thus, the job becomes a frustrating exercise in futility.

BRIEF DESCRIPTION OF THE INVENTION

The instant invention is a hand tool that has a pliers-like body and a special head. The head has a pair of parallel teeth that fit onto the lands above the grooves of a zipper guide. As the tool is squeezed, the jaws force the grooves lands down and closed uniformly and symmetrically. Appropriate pressure is applied to set the closure for the zipper teeth. In this way, the tool can work the groove lands on all types of zippers quickly and easily, such as those found on tents, clothing, tote bags, luggage and many other things.

BRIEF DESCRIPTION OF THE DRAWINGS

FIG. 1 is a left side perspective view of the invention.

FIG. 2 is a right side perspective view of the invention showing the jaws open.

FIG. 3 is an enlarged right side perspective view of the invention showing the jaws open.

FIG. 4 is a front detail view of a jaw.

2

FIG. 5 is a front view of a zipper guide in a normal operating configuration.

FIG. 6 is a front view of a zipper guide in a bent or defective configuration.

5 FIG. 7 is a detail view of the invention being applied to a zipper guide to repair the zipper guide.

DETAILED DESCRIPTION OF THE
INVENTION

10 Referring now to FIGS. 1, 2 and 3, the invention 1 is a hand tool that has a pliers-like body 2 and a special head 3. The pliers-like body is formed of two handle portions 2a and 2b that are joined by a nut or rivet 2c. This type of construction is identical to that found in a pair of slip joint pliers, that are common to the art.

Unlike a standard pair of pliers, which has a gripping head, the head 3 of the instant invention has a pair of parallel jaws 4 that are designed to fit onto the grooves 101 of a 20 zipper guide (see FIG. 5). The head 3 has a right side 3a and a left side 3b that are formed on the top of the handles 2a and 2b as shown.

25 Referring now to FIGS. 3 and 4, details of the jaws 4 are shown. FIG. 3 shows each jaw 4 as having a base portion 5 and a bifurcated upper portion 6. The upper portion 6 is a pair of members that have an angled tip 7. The tip 7 is designed to fit over (or under) one of the grooves of the zipper guide, as discussed below.

30 Note that the heads 3 and jaws 4 of the device are parallel and symmetrical. This allows the user to fit the tool onto all sides of a damaged zipper guide simultaneously, which result in a repair made in one operation. This eliminates the need to adjust one side at a time. Moreover, it eliminates the problem of unbalanced adjustments, which require multiple adjustments to correct.

35 Referring now to FIGS. 5 and 6, an oversized view of a 40 representative zipper guide 100 is shown. The zipper guide has two grooves 101, formed by joining a top portion 104 and a bottom portion 105 by a center web 103. FIG. 6 shows an oversized view of a damaged zipper. Here, the top and bottom portions have been forced apart, making the guide unusable. To correct this problem, people use tools such as 45 pliers to squeeze the grooves closed. This procedure is clumsy at best. Closing the grooves by such means often results in unbalanced grooves. These must be reopened and then squeezed down again until the repair is complete. Occasionally, the use of such tools breaks the zipper guide, making it completely unusable.

50 FIG. 7 shows the tool in use. Here, the jaws 4 are placed such that the tips 7 align with the grooves 101. Note how the jaws 4 simultaneously fit against the top and bottom of both sides of the zipper guide 100. As the tool 1 is squeezed, the tips 7 force the grooves down uniformly and symmetrically.

55 In this way, the tool can narrow the grooves on all types of zippers quickly and easily. Such a tool can be used on all types of zippers, such as those found on tents, clothing, tote bags, luggage and many other things.

The present disclosure should not be construed in any 60 limited sense other than that limited by the scope of the claims having regard to the teachings herein and the prior art being apparent with the preferred form of the invention disclosed herein and which reveals details of structure of a preferred form necessary for a better understanding of the invention and may be subject to change by skilled persons within the scope of the invention without departing from the concept thereof.

I claim:

1. A tool for repairing zippers comprising:
  - a) a pair of handles, rotatably attached about a pivot point; and
  - b) a pair of jaws formed on said pair of symmetrical handles wherein each jaw has a first curved vertical member, extending upward from each handle of said pair of handles from the pivot point, a second curved vertical member attached midpoint to said first curved vertical member by a horizontal bridge member, the first and second curved vertical members being substantially parallel with the gap defined in-between, and further wherein said first and second curved vertical members have a flattened angled tip formed thereon.
2. A method of repairing a zipper using a tool having a pair of handles, rotatably attached about a pivot point, a pair of symmetrical jaws formed on said pair of handles wherein each jaw has a first curved vertical member, extending upward from each handle of said pair of handles from the pivot point, a second curved vertical member attached

midpoint to said first curved vertical member by a horizontal bridge member, the first and second curved vertical members being substantially parallel with a gap defined in-between, and further wherein said first and second curved vertical members have a flattened angled tip formed thereon, comprising the steps of:

- a) opening said pair of handles, thereby opening said pair of jaws;
- 10 b) placing a zipper guide between said pair of jaws, such that the flattened angled tip of each vertical member is adjacent to said zipper guide;
- c) closing said pair of handles, thereby clamping said pair of jaws onto said zipper guide; and
- d) applying pressure to said pair of handles, thereby pressing said zipper guide between said pair of jaws, said pressure acting to close the spacing of said zipper guide.
